UNITED STATES PATENT OFFICE.

ALFRED H. HUMPHREY, OF NEW YORK, N. Y.

COMBINATION GAS AND ELECTRIC LAMP.

1,125,907.

Specification of Letters Patent.

Patented Jan. 19, 1915.

Application filed September 5, 1914. Serial No. 860,330.

To all whom it may concern:

Be it known that I, ALFRED H. HUMPHREY, a citizen of the United States, residing in the city and county of New York, State of New York, have invented certain new and useful Improvements in Combination Gas and Electric Lamps, of which the following is a specification.

This invention relates to improvements in combination gas and electric lamps.

My invention relates particularly to improvements in combination gas and electric lamps of indirect type or semi-direct type as they are sometimes called, that is, lamps in which the light is reflected upwardly from an opaque or a translucent globe closing the lower part of the lamp.

The main objects of this invention are: First, to provide an improved combination gas and electric lamp of the indirect type. Second, to provide an improved combination gas and electric lamp of the indirect type in which the globe is closed beneath and open at the top and the parts so arranged that the light rays radiating and reflected upwardly are practically shadowless. Third, to provide an improved combination gas and electric lamp of the indirect type in which the parts are so arranged that the products of combustion escape without unduly heating the electric lamps and their connections and at the same time do not interfere with the air supply to the gas burner at the mixing tube parts or at the point of combustion. Fourth, to provide an improved combination gas and electric lamp in which the burner and the electric lamps are so disposed that the light is uniformly distributed and without "spot" light effects.

Further objects, and objects relating to structural details, will definitely appear from the detailed description to follow.

I accomplish the objects of my invention by the devices and means described in the following specification.

The invention is clearly defined and pointed out in the claims.

A structure which is a preferred embodiment of my invention is clearly illustrated in the accompanying drawing forming a part of this specification, in which:

Figure I is a side view of a structure embodying the features of my invention. Fig. II is a plan view of the bottom portion of the lamp, the side members of the frame being shown in the horizontal section. Fig.

III is an enlarged detail plan view showing the mounting of one of the electric lamps. Fig. IV is a detail inside elevation showing further details of the mounting of one of the electric lamps. Fig. V is a detail horizontal section on a line corresponding to line 5-5 of Fig. IV. Fig. VI is a detail vertical section on a line corresponding to broken line 6-6 of Fig. III. Fig. VII is a detail horizontal section on a line corresponding to line 7-7 of Fig. I, showing details of the top of the lamp. Fig. VIII is a detail vertical section on a line corresponding to line 8-8 of Fig. VII. Fig. IX is a detail vertical section on a line corresponding to line 9-9 of Fig. VII.

In the drawing similar reference characters refer to similar parts throughout the several views, and the sectional views are taken looking in the direction of the little arrows at the ends of the section lines.

Referring to the drawing the supply pipe 1 is adapted as a support for the lamp. I provide a skeleton frame consisting in the structure illustrated of the coupling or top member 2 having radial arms 3. Depending from these arms 3 are rod like side members 4, 5, 6, and 7. These side members diverge downwardly to the band-like annular supporting member 8 mounted on their lower ends. At the other ends of the side members 4 is an ornamental member 9 which embraces the top member 2. The side members 4 are preferably provided with ornamental portions 10 at their upper ends and ornamental portions 11 at their lower ends which terminate in cross portions 12 disposed on the inside of and secured to the supporting member 8 by means of screws 13. The supply pipe 1 is provided with an ornamental ceiling member 14. The side member 4 is adapted as a gas delivery conduit. The side member 5 is adapted as a conduit for the circuit wires. The side member 6 is adapted as a gas conduit for the pilot burner. The side member 7 in the structure illustrated is a dummy.

The burner 15 is provided with a horizontally disposed mixing tube 16 arranged in the plane of the supporting member 8, the width of the supporting member being approximately the diameter of the mixing tube. The burner is supported by the mixing tube and the inwardly projecting rod 17 which is passed through an ear 18 on the burner, the burner being secured on the rod by the nuts 19. The burner is thus cen-

trally supported without encumbering the space within the lamp. The pilot burner 20 projects inwardly from the conduit 6 into suitable proximity to the burner.

5 The main burner is controlled by a valve designated generally by the numeral 22 while the pilot is regulated by the valve 23. As the details of these valves form no part of my present invention, they are not 10 illustrated or described in detail herein.

15 The globe holder member 24 is hinged at 25 to the supporting member 8 so as to embrace the same as shown, the globe holder being held in its closed position by the 20 spring pins 26. Between the supporting member 8 and the globe holder, I arrange brackets for the circuit wires 27. These 25 brackets in the structure illustrated consist of the blocks 28 of insulating material and the clip members 29, the blocks being secured to the clip members by the bolts 30. The clip members are provided with flanges 31 which embrace the supporting band 8 as clearly shown in Fig. VI, the wire brackets 30 are secured upon the supporting members by means of the lamp supporting brackets 32 which are arranged on the inner side 25 of the supporting member 8 and slidably engage the flanges of the wire supporting brackets. These brackets 32 are Y-shaped, the inwardly projecting arms 33 having threaded nipples 34 upon which the lamp sockets 35 are mounted. The lamps 36 are supported on these brackets in a chord-like 30 relation to the supporting member and in substantially the plane of the supporting member although they are preferably slightly inclined as indicated in Fig. IV. The circuit wires are passed down through 35 the conduit 5 and are supported by the wire supporting brackets between the globe holder and supporting members as clearly shown in Fig. II, suitable terminals 37 lead from the wires 36 to the lamps. The circuit 40 wires are retained upon the insulating blocks by means of the caps 38 also of insulating material. By this simple means, the lamp and circuit wire brackets are properly supported. The lamps may be positioned 45 as desired, that is, the same general structure is adapted for two, three or four electric lamps as may be desired.

50 The electric lamps in the position in Fig. II are out of the way of the products of combustion, which pass upwardly around in the burner and at the same time they are positioned so that the light therefrom blends with the light from the gas burner producing a highly satisfactory result.

55 The globe 39 is open at the top and is mounted upon the globe holder to embrace the burner and lamps from below. The globe is preferably semi-opaque or translucent.

60 The structure being entirely open above

the burner, there are no operating or metal parts to obstruct light rays radiating from the burners and lamps and reflected from the inside of the globe upwardly through the skeleton frame. Further, all the operating parts of the lamp and metal connections, the ornamental side members, the ornamental globe ring, together with the valves are entirely outside of the path of the products of combustion and do not become heated enough to interfere with the successful operation of the lamp or to spoil the finish. Further, owing to the unobstructed center above the burner and the wide open globe of reflected light rays are distributed from the 70 inner surface of the globe over a wide area and the reflected heat rays are to a large degree distributed as are the light rays. The lamp being entirely open above causes a central upward current and draws fresh air to 75 the burner to properly maintain combustion at that point and also to furnish a supply of fresh air to the port 40 on the mixing tube. The light is reflected and radiated from the lamp upwardly so that there are no 80 shadows which is a highly desirable feature. My improved lamp is also very desirable on account of the ease with which it may be cared for as the burner parts and lamps are all fully accessible when the globe 85 is open both from above and from below.

I have illustrated and described my improved lamp in detail in the form in which I have embodied the same. I have not attempted to illustrate or describe the various 90 modifications which I contemplate as practical and in some cases desirable as the disclosure made will enable those skilled in the art to which my invention relates to embody or adapt the same as may be desired. I desire, however, to be understood claiming 95 my improvements specifically in the form illustrated as well as broadly within the scope of the appended claims.

Having thus described my invention, 100 what I claim as new and desire to secure by Letters Patent, is:

1. In a combined gas and electric lamp, the combination of a skeleton frame comprising a top member, side members depending therefrom, one of said side members being adapted as a gas delivery conduit and another as a circuit wire conduit, and a band-like supporting member on the lower ends of said side members, an inverted 115 burner comprising a horizontally disposed mixing tube arranged with its burners centrally of said supporting member and in approximately the plane thereof, an annular globe holder member mounted upon and 120 embracing said supporting member, insulating blocks disposed between said globe holder and supporting members, clip members on which said insulating blocks are 125 mounted disposed on the outer side of said 130

65 The structure being entirely open above

- supporting member and provided with facing channeled flanges embracing the same, Y-shaped lamp supporting brackets disposed within said supporting member and 5 slidably engaging said channeled flanges of said clip members whereby they are secured to the said supporting member and the lamp brackets are supported, electric lamps mounted on the inwardly projecting arms 10 of said brackets in a chord-like relation to the said supporting member and in approximately the plane thereof, circuit wires arranged through said side member adapted as a wire conduit, the ends of the wires beyond 15 the said side members being mounted on the said insulating blocks between the said supporting and globe holder members and connected to said electric lamps, and a globe open at its upper end mounted on 20 said globe holder.
2. In a combined gas and electric lamp, the combination of a skeleton frame comprising a top member, side members depending therefrom, one of said side members being 25 adapted as a gas delivery conduit and another as a circuit wire conduit, and an annular supporting member on the lower ends of said side members, an inverted burner disposed centrally of said supporting member and in approximately the plane thereof, a globe holder member embracing said supporting member, insulating blocks disposed 30 between said globe holder and supporting members, clip members on which said insulating blocks are mounted disposed on the outer side of said supporting member, lamp brackets disposed within said supporting member and engaging said clip members whereby the brackets and the clip members 35 are secured to said supporting member, electric lamps mounted on said brackets in a chord-like relation to the said supporting member and in approximately the plane thereof, lamp circuit wires disposed through 40 said side member adapted as a wire conduit, the ends of the wires beyond the said side member being mounted on said insulating blocks between the said supporting and globe holder members, and a globe carried by said globe holder member.
3. In a combined gas and electric lamp, the combination of a skeleton frame comprising a top member, side members depending therefrom, one of said side members 45 being adapted as a gas delivery conduit and another as a circuit wire conduit, and an annular supporting member on the lower ends of said side members, an inverted burner disposed centrally of said supporting member, a globe holder member embracing said supporting member, insulating blocks disposed between said globe holder and supporting members, clip members on which said insulating blocks are mounted disposed on the outer side of said supporting member and provided with facing 50 channeled flanges embracing the same, lamp supporting brackets disposed within said supporting member and slidably engaging said channeled flanges of said clip members whereby they are secured to the said supporting member and the brackets are supported, electric lamps mounted on said brackets, circuit wires mounted on the said insulating blocks between the said supporting and globe holder members, and a globe carried by said globe holder member.
4. In a combined gas and electric lamp, the combination of a frame comprising a band-like supporting member, a gas burner disposed centrally of said supporting member in approximately the plane thereof, a globe holder member mounted upon and embracing said supporting member, insulating blocks disposed between said globe holder and supporting members, clip members on which said insulating blocks are mounted disposed on the outer side of said supporting member and provided with facing channeled flanges embracing the same, lamp supporting brackets disposed within said supporting member and slidably engaging said channeled flanges of said clip members whereby they are secured to the said supporting member and the brackets are supported, electric lamps mounted on said brackets, circuit wires mounted on the said insulating blocks between the said supporting and globe holder members, and a globe carried by said globe holder member.
5. In a combined gas and electric lamp, the combination of a frame comprising a band-like supporting member, a gas burner disposed centrally of said supporting member, a globe holder member mounted upon and embracing said supporting member, insulating blocks disposed between said globe holder and supporting members, clip members on which said insulating blocks are mounted disposed on the outer side of said supporting member and provided with facing channeled flanges embracing the same, lamp supporting brackets disposed within said supporting member and slidably engaging said channeled flanges of said clip members whereby they are secured to the said supporting member and the brackets are supported, electric lamps mounted on said brackets, circuit wires mounted on the said insulating blocks between the said supporting and globe holder members, and a globe carried by said globe holder member.
6. In a lamp, the combination of a frame comprising a band-like supporting member, a globe holder member embracing said supporting member, insulating blocks disposed between said globe holder and supporting member.

members, clip members on which said insulating blocks are mounted disposed on the outer side of said supporting member and provided with facing channeled flanges embracing the same, lamp supporting brackets disposed within said supporting member and engaging said channeled flanges of said clip members whereby they are secured to the said supporting member and the brackets 10 are supported, electric lamps mounted on said brackets, circuit wires mounted on the said insulating blocks between the said supporting and globe holder members, and a globe carried by said globe holder member.

15 7. In a combined gas and electric lamp, the combination of a frame comprising an annular supporting member, a gas lamp disposed centrally of said supporting member and approximately in the plane thereof, a globe holder member mounted upon and embracing said supporting member, wire supporting brackets disposed between said globe holder and supporting members, lamp brackets disposed within said supporting member and engaging said wire brackets whereby the wire and lamp brackets are secured to said supporting member, electric lamps mounted on said lamp brackets in a chord-like relation to said supporting member and 20 in approximately the plane thereof, circuit wires mounted on said wire brackets between said supporting and globe holder members, and a globe carried by said globe holder member.

25 8. In a lamp, the combination of a frame comprising an annular supporting member, a globe holder member mounted upon and embracing said supporting member, wire supporting brackets disposed between said globe holder and supporting members, lamp brackets disposed within said supporting member and engaging said wire brackets whereby the wire and lamp brackets are secured to said supporting member, electric lamps mounted on said lamp brackets, circuit wires mounted on said wire brackets between said supporting and globe holder members, and a globe carried by said globe holder member.

30 9. In a combined gas and electric lamp, the combination of a frame comprising a band-like supporting member, a gas lamp disposed centrally in said supporting member, a globe holder member embracing said supporting member, wire supporting brackets disposed between said globe holder and supporting members, lamp brackets disposed within said supporting member and engaging said wire brackets whereby the wire and lamp brackets are secured to said supporting member, electric lamps mounted on said lamp brackets, circuit wires mounted on said wire brackets between said supporting and globe holder members, and a globe carried by said globe holder member.

35 10. In a combined gas and electric lamp, the combination of a frame comprising a band-like supporting member, a gas lamp disposed centrally in said supporting member, a globe holder member embracing said supporting member, wire supporting brackets disposed between said globe holder and supporting members, lamp brackets disposed within said supporting member, electric lamps mounted on said lamp brackets, circuit wires disposed between said globe holder and supporting members and mounted on said wire brackets, and a globe carried by said globe holder member.

40 11. In a combined gas and electric lamp, the combination of a skeleton frame comprising a top member, side members depending therefrom, one of said side members being adapted as a gas delivery conduit and another as a circuit wire conduit, and an annular supporting member on the lower ends of said side members, a gas burner disposed centrally of said supporting member and in approximately the plane thereof, a globe holder member embracing said supporting member, circuit wire brackets disposed between said supporting and globe holder members, lamp brackets disposed within said supporting member, electric lamps mounted on said lamp brackets in a chord-like relation to the said supporting member and in approximately the plane thereof, lamp circuit wires disposed through said side member adapted as a wire conduit, the ends of the wires beyond the said side member being mounted on said wire supporting brackets between the said supporting and globe holder members, and a globe carried by said globe holder member.

45 12. In a combined gas and electric lamp, the combination of a skeleton frame comprising a top member, side members depending therefrom, one of said side members being adapted as a gas delivery conduit and another as a circuit wire conduit, and an annular supporting member on the lower ends of said side members, a gas burner disposed centrally of said supporting member, a globe holder member embracing said supporting member, circuit wire brackets disposed between said supporting and globe holder members, lamp brackets disposed within said supporting member, electric lamps mounted on said lamp brackets in a chord-like relation to the said supporting member and in approximately the plane thereof, lamp circuit wires disposed through said side member adapted as a wire conduit, the ends of the wires beyond the said side member being mounted on said wire supporting brackets between the said supporting and globe holder members, and a globe carried by said globe holder member.

50 13. In a combined gas and electric lamp,

the combination of a skeleton frame comprising a top member, side members depending therefrom, one of said side members being adapted as a gas delivery conduit and another as a circuit wire conduit, and an annular supporting member on the lower ends of said side members, a gas burner disposed centrally of said supporting member, a globe holder member embracing said supporting member, circuit wire brackets disposed between said supporting and globe holder members, lamp brackets disposed within said supporting member, electric lamps mounted on said lamp brackets, lamp circuit wires disposed through said side member adapted as a wire conduit, the ends of the wires beyond the said side member being mounted on said wire supporting brackets between the said supporting and globe holder members, and a globe carried by said globe holder member.

14. In a gas lamp, the combination of a supporting frame comprising a top member, side members depending therefrom, one of said side members being adapted as a gas delivery conduit and another as a circuit conduit, an annular supporting member on the lower ends of said side members, an inverted burner disposed in approximately the plane of said supporting member, electric lamps arranged within and mounted upon said supporting member in approximately the plane thereof, circuit wires for said lamps disposed through said side member adapted as a wire conduit, and a globe open at its upper end embracing said burner and lamps from below.

15. In a combined gas and electric lamp, the combination of a skeleton frame comprising a top member, an annular supporting member, and side members diverging downwardly from said top member to said supporting member, one of said side members being adapted as a gas delivery conduit and another as a circuit wire conduit, a burner disposed centrally within said annular supporting member with its body portion in the plane thereof, electric lamps mounted on said supporting member, said lamps being disposed in an approximately horizontal position in the plane of said supporting member and in a chord-like relation thereto, circuit wires disposed through said member adapted as a wire conduit and connected to said lamps, and a translucent globe embracing said lamps and burner from below, the passage of the light and the products of combustion around the burner and between the side, top, and supporting members of said frame being unobstructed.

16. In a combined gas and electric lamp, the combination of a skeleton frame comprising a top member, a supporting mem-

ber, and side members by which said supporting member is carried depending from said top member, one of said side members being adapted as a gas delivery conduit and another as a circuit wire conduit, a burner disposed centrally within said supporting member, electric lamps mounted on said supporting member, said lamps being grouped about said burner, circuit wires disposed through said member adapted as a wire conduit and connected to said lamps, and a translucent globe embracing said electric lamps and burner from below, the passage of the light and the products of combustion around the burner and between the side, top, and supporting members of said frame being unobstructed.

17. In a combined gas and electric lamp, the combination of a skeleton frame comprising a top member, side members depending therefrom, one of said side members being adapted as a gas delivery conduit, and another as a circuit wire conduit, and an annular supporting member on the lower ends of said side members, an inverted burner disposed centrally of said supporting member and in approximately the plane thereof, electric lamps mounted on said supporting member in a chord-like relation thereto and in approximately the plane thereof, lamp circuit wires disposed through said side member adapted as a wire conduit, a globe supporting means, and a translucent globe open at its upper end embracing the said burner and lamps from below whereby light may radiate from the burner and lamps and may be reflected from the inside the globe upwardly through said frame.

18. In a combined gas and electric lamp, the combination of a skeleton frame comprising a top member, a supporting member, and side members by which said supporting member is carried depending from said top member, one of said side members being adapted as a gas delivery conduit, a burner disposed centrally within said supporting member, electric lamps mounted on said supporting member, said lamps being grouped about said burner, and a translucent globe embracing said electric lamps and burner from below, the passage of the lights and the products of combustion around the burner and between the side, top, and supporting members of said frame being unobstructed.

In witness whereof, I have hereunto set my hand and seal in the presence of two witnesses.

ALFRED H. HUMPHREY. [L. s.]
